UNITED STATES PATENT OFFICE.

ALEXANDER D. FERGUSON, OF CHICAGO, ILLINOIS, ASSIGNOR TO SULLIVAN MACHINERY COMPANY, A CORPORATION OF MASSACHUSETTS.

COMPRESSOR.

Application filed August 11, 1922. Serial No. 581,253.

My invention relates to compressors, and more particularly to compressor systems provided with means for effecting the progressive unloading thereof whereby with a constant speed drive it may be possible for the compressor output to be varied in such manner as to maintain the discharge line pressure within certain desired limits.

An object of my invention is to provide an improved compressor mechanism. Another object of my invention is to provide an improved compressor mechanism having improved partial or step by step unloading means. A further object of my invention is to provide an improved compressor system having improved means for effecting a step by step unloading of the entire system in which less of complication is involved than in such systems of other types. Other objects and advantages of my invention will hereinafter more fully appear.

In the accompanying drawings I have shown for purposes of illustration one form which my invention may assume in practice.

In these drawings,—

Fig. 1 is a diagrammatic view of a compressor system provided with the illustrative form of my invention.

Fig. 2 is a view in central vertical section through the intake unloading means provided for use on the low pressure cylinders of the compressor units, certain parts being shown in elevation.

Fig. 3 is a central vertical section through the pilot mechanism controlling the operation of my improved system.

Fig. 4 is an elevation of the same viewed from a different angle.

Fig. 5 is a transverse section on the line 5—5 of Fig. 3.

Fig. 6 is a detail sectional view through the unloading means for one end of one of the high pressure cylinders.

In the form of my invention shown for purposes of illustration in the accompanying drawings I have shown it embodied in a twin angle compound compressor system which comprises a pair of angle compound

compressors 1 and 2, each having low pressure cylinders 3 and high pressure cylinders 4, the low pressure cylinders being supplied with air from intake lines 5 and discharging through intercoolers 6 to the

high pressure cylinders 4 which, in turn, 55 discharge by way of a discharge line 7 to a receiver or other point of storage or use.

In the customary construction the compressors 1 and 2 are driven from a common crank shaft 7', but in order to permit the 60 more intelligible disclosure of the piping system employed, I have shown the compressor units 1 and 2 set one behind the other instead of in their customary relation. As each of the units is the same in 65 its general details and as it is by the particular nature of the piping connections with the pilot mechanism that the progressive or step by step unloading of the system is accomplished, it will suffice if I 70 describe the operative unloading mechanism for one compressor and then describe the control connections and pilot valve for both units.

Accordingly, considering the compressor 75 unit 1 and noting particularly Fig. 2, it will be observed that the intake line 5 communicates with a casing 8 transversely of which there extend partition members 9 and 10, the partition members 9 and 10 being connected 80 at about the longitudinal center of the casing 8 by a vertical partition 11 so that separate chambers 12 and 13 are formed and these chambers 12 and 13 communicate respectively with the inlet valve for the front and rear 85 ends of the low pressure cylinder 3. Above the partition 10 is a chamber 14 which is connected with the chamber below the partition 9 in a manner which will shortly be made apparent. The partitions 9 and 10 at opposite sides of the partition 11 are traversed 90 by circular ports 15 and 16, which ports are surrounded by valve seats 17 and 18, the ports being identical at each side of the partition 11 and the upper ports being somewhat 95 larger than the lower to permit the insertion of the valve mechanism. Slidable through the openings 15 and 16 are valve members which for purposes of convenience will be 100 designated 20 for the rear end of the cylinder and 21 for the front end thereof, these valve members each comprising a pair of circular valve seat portions 22 and 23 which are 105 respectively adapted to seat upon the seats 17 and 18 and from each of the valve seating portions 22 and 23 there depend supported by suitable ribs 24 and 25 guiding portions 26 and 27 which serve to maintain the

valves 20 and 21 properly centered within their seats during reciprocation thereof. The valves are hollow throughout their length as indicated at 28, thereby permitting the connection of the chamber 14 with the chamber below the partition 9. Extending centrally through the valve members are valve stems 30 which are connected as at 31 to cross arms 32, these latter being in turn connected by springs 33 with cross arms 34 arranged at the top of operating cylinders 35 which are mounted as indicated at 36 upon heads 37 closing the top of the casing 8. Within the cylinders 35 there are pistons 38 reciprocable, these pistons engaging stems 39 connected with the stems 30 and being operative to force the valves 20 or 21, as the case may be, closed on admission of air to their cylinder 35. Suitable stops 42 limit the upward travel of the pistons 38.

For the purpose of greater convenience in subsequent reference to the unloading system as a whole, the unloading mechanism for the front end of the low pressure cylinder of unit No. 1 will be designated generally 43, that for the rear end thereof 44, that for the front end of the low pressure cylinder of the unit No. 2 45, and that for its rear end 46.

It will be obvious that any suitable type of inlet or discharge valves may be employed upon the low pressure cylinders, the mode of operation of my mechanism being absolutely independent of the nature of the valves used.

On the high pressure cylinders I prefer for reasons which will shortly be apparent to employ a type of combined inlet and discharge mechanism which is disclosed in the application of one Frank A. Halleck, Serial No. 532,741, filed Jan. 30, 1922, this mechanism comprising a pair of spaced valve seat elements 51 and 52 coaxially arranged with respect to each other and disposed at opposite sides of a port 53 communicating with the end of the cylinder bore whereby an annular chamber 54 communicating with the cylinder bore of the high pressure cylinder is formed between the valve seat members 51 and 52. Suitable annular valves 55 normally held closed by transversely flexed springs 56, which are supported by guards 57, close the ports 58 through the valve seat member 52 and so

control the discharge of pressure to a passage 59 which communicates with the discharge line 7. Suitable valves 60 normally held closed by transversely flexed springs 61 supported by a guard member 62, normally maintain passages 63 communicating with the intake chambers 64 of the high pressure cylinder closed. It will be evident that during the normal operation of the compressor, upon the suction strokes of the high pressure piston, the valve 60 will be unseated by

intercooler pressure during the suction

strokes, and that during the discharge strokes the valves 55 will be unseated by the pressure within the cylinder. One or more of these valve mechanisms may be used at each end of the high pressure cylinders of both the units 1 and 2. Disposed within the intake chambers 64 at the upper ends of the high pressure cylinders 4 of units 1 and 2, there are mechanisms including valve seat members 65 bolted as at 66 in position upon the tops of the inlet valve cages 51 and each having a port 67 traversing the same, which port is surrounded by a valve seat 68. These mechanisms also each include a valve member 69 adapted to seat upon the valve seat 68 and formed at the lower end of a piston member 70 which is reciprocable in a cylinder 71 supported on a closure member 72 and projecting through an opening in the upper end of the cylinder head of the cylinder 4. The piston 70 is normally held in raised position with the valve member 69 spaced from the seat 68 by a relatively heavy spring 74 which engages the lower side of the head of the piston 70 and is supported upon the top of the valve cage member 51. Means for supplying fluid pressure to the upper end of the cylinder 71 to act upon the piston 70 and force the same downward to close the valve 69 is shown at 75 and will be more fully described later, it being evident that when receiver pressure is transmitted through the pipe 75 the piston will be forced downward and the inlet valve shut off from all communication with the intercooler while without pressure in the line 75 the valve 69 will stand open and the inlet valve will be free to admit charges of air from the intercooler. To permit the escape of fluid from above the piston 70 any suitable leakage means may be provided, as for example a pin hole 76. These mechanisms for the units 1 and 2 are respectively designated 81 and 82. Each of the high pressure cylinders 4 is also in addition provided with automatic means, herein numbered 85, of the type shown in the patent to H. C. Johansen 1,404,176, Jan. 17, 1922, which is operative to permit the automatic discharge, when the compressor is completely unloaded, of any small leakage past the intake closure valves directly to the atmosphere from the high pressure cylinders.

For the purpose of controlling the supply of operating fluid to the receiver pressure operated unloading means 43, 44, 45, 46, 81 and 82, I have devised an improved pilot valve mechanism which I shall now proceed to describe. This pilot valve mechanism is generally designated 100 and comprises a series of valve members which are annular in construction and which are designated respectively 101, 102, 103 and 104, which valve members are controlled by means which I shall now more specifically describe. The

valve members 101 to 104 respectively are arranged to cooperate with seats 105, 106, 107, and 108, the several seats being plane and each containing an annular groove 109, 5 the several annular grooves 109 communicating respectively by passages respectively numbered 110, 111, 112, and 113 with pipes 114, 115, 116 and 117, which pipes I will shortly refer to again. Each of the seats 105 to 108 inclusive is traversed by a central passageway, these passageways being of uniform diameter and being indicated at 118. Extending longitudinally through the several passageways mentioned is a stem 120 10 formed at its top with a plunger or piston 121 upon which a spring 122 housed in the casing 123 and adjustable by means of a follower 124 coacts. Formed upon the stem 120 is a collar 125 which is adapted to engage 15 after a predetermined movement from a given lower position which will be more fully described later, the valve member 101 and lift it from its seat 105. Resting upon the top of the valve member 101 is a sleeve 126 20 which is of slightly less length than the distance between the valve member 101 and the valve member 102 when both are seated. This sleeve is adapted to be raised on upward movement of the valve 101 and after sufficient upward movement to engage and lift the valve member 102. A similar sleeve co-operating with the valve 103 in a similar manner and designated 127 is superimposed 25 on the valve 102 and a further similar sleeve 128 is arranged to be lifted by the valve member 103 and to raise the valve member 104. The piston 121 is slideable in a cylinder 129 formed in the casing 123 and fluid pressure from a suitable source is conducted by 30 a passage 130 to chambers 131, 132, 133, and 134 in which the valve members 101 to 104 respectively are located. This pressure normally tends, of course, to maintain the several valve members seated and as it will be 35 observed that each of the valve members is raised successively alone from its seat and as it will be observed that the valve members are all of substantially equal diameter with the piston 121, it will be apparent that the 40 pressure of air acting beneath the piston 121 is such as to practically neutralize the work necessary in raising one of the valve members off its seat. The stem 120 passes through a suitable bore 136 downward into a space 45 formed between a pair of support members 137 formed integral with a support 138. Secured to the support 138 is an expansible diaphragm chamber 139 to whose interior 50 fluid may be conducted by a passage 141 140 and a series of grooves 142 formed in a member 143 which threadedly engages the lower head 144 of the diaphragm chamber and holds it fixedly in position on the member 138. The member 143 is traversed by a passage 145 through which a plunger 146, alined 55 with the stem 120 and having suitable sealing grooves 147 snugly extends, the plunger 146 engaging at 148 the upper head 149 of the diaphragm chamber. The plunger 146 is provided at its lower end with a handle 70 150 and is traversed by a series of four parallel transverse passageways 151, 152, 153, and 154. The member 143 is provided with a depending sleeve 155 in which a series of holes 156, 157, 158 and 159 are formed, these 75 holes being so spaced relative to each other and to the holes 151 to 154 that the hole 151 will register with the hole 159 with a very slight upward movement of the stem 146, while progressively further upward movements of the stem 146 will successively cause 80 registration of the holes 152 and 158, 153 and 157, and 154 and 156. When the first of these pairs of holes register, valve 101 is unseated and as each successive pair of holes 85 is brought into register an additional valve is opened. The function of this mechanism will shortly be explained.

Leading from a receiver to which the compressors discharge, or from their common 90 discharge line, is a passage or connection 160 controlled by a stop valve 161 and provided with a strainer 162 to prevent the passage of impurities or solid matter to the valve mechanism. Beyond the strainer 162 is a 95 T 163 from which a connection 164 leads to the passageway 130 previously described. From the other end of the T a connection 165 leads to the pop valve 166 which pop valve works on the principle of the ordinary 100 safety valve, that is, it opens when a desired pressure is reached in the line 160 and permits a pressure equal to the excess above the desired pressure in line 160 to pass through the valve before it again closes. 105 The chamber above the valve in the pop valve 166 communicates with the passage 141 so that a pressure equal to the excess above the seating of the pop valve will be transmitted to the diaphragm chamber 140. 110 Upon the top of the pop valve 166 is a safety valve 167 loaded to prevent building up of more than a desired pressure in the diaphragm chamber 140. A suitable pin 115 hole leak or adjustable leak 166' as may be desired is arranged at any suitable point between the pop valve 166 and the limits of the diaphragm chamber whereby the pressure in the chamber 140 will promptly fall 120 on closure of the pop valve 166. Leakage may also be permitted around the plunger 146, a shoulder 168 thereon then cooperating with the top of the member 143 in preventing leakage when the diaphragm is collapsed to its smallest size. 125

It will be recalled that a series of pipes 114, 115, 116, and 117 have been described above. These pipes are connected to the several unloading means 43, 44, 45, 46, 81 130 and 82 as follows: The pipe 114 connects by

branches 175 and 176 respectively to the low pressure intake closure type unloading means 44 and the high pressure unloading means 81 of unit No. 1, the pipe 115 connects to the other low pressure unloading means 43 of unit No. 1. Pipe 116 connects by suitable branches 177 and 178 respectively to the low pressure unloading means 46 and the high pressure unloading means 82 of unit No. 2, while the passage 117 connects to the second low pressure unloading means 45 of unit No. 2.

From the description of the mechanism itself, the mode of operation of this invention will already be apparent, but it may be briefly summarized as follows: Let it be assumed that the compressor is supplying air to a plant in which the demand for air is such as to cause the compressor to operate at full load to maintain the necessary supply line pressure. Now let it be assumed that the demand for air falls off slightly. As a result, since the compressor is being driven at a constant speed, the pressure in the compressor discharge line, i. e. the supply line to the plant, will rise and as a result the pop valve 166 which is set to open when the pressure exceeds the desired line pressure, say 100 pounds, will open and pressure will be transmitted into the diaphragm chamber 140. If the pressure rises to a value say two or three pounds in excess of the desired 100 pounds, the expansion of the diaphragm chamber will cause the collar 125 to raise the valve 101 and pressure will be supplied to the line 114. As a result, air will be supplied to close the intake to the head end of the low pressure cylinder and to the head end of the high pressure cylinder, this being accomplished by means of the unloading mechanisms 44 and 81, and the compressor system will then operate at three-quarter load, unit No. 2 continuing to operate at full load and unit No. 1 acting as a compressor having single acting high and low pressure cylinders. If the demand for air falls off sufficiently to cause the pressure to reach a value a few pounds higher than was necessary to open valve 101, valve 102 will be raised by continued upward movement of valve 101, causing the sleeve 118 to lift valve 102. Pressure will then be transmitted through pipe 115 to unloading means 43 and the intake to the crank end of low pressure cylinder of unit No. 1 will also be closed. Unit No. 1 will then be completely unloaded since no air except a small quantity which may leak in can secure admission to the compressor. The small quantity of air which may leak past the closed intake controlling valves 20 and 21 or which may leak in through the packings around the piston rods, etc., will be discharged direct to the atmosphere by the automatic means 85 previously de-

scribed. If the pressure in the discharge line rises still further, the valve 103 will be opened and pressure supplied through pipe 116 to close the connections between the head ends of the low and high pressure cylinders of unit No. 2 and the points of suction of these cylinders, that is, the low pressure cylinder can no longer draw in air from the atmosphere and the high pressure cylinder can no longer draw in air from the intercooler, as to their head ends respectively. If the demand falls off still further or ceases entirely, the valve 104 will finally be opened and transmission of pressure through line 117 to the unloading means 45 will completely unload unit No. 2. As the demand for air increases, the compressor units will be progressively reloaded in an obvious manner as the valves 104, 103, 102, and 101 are successively closed.

In case the demand for air over a long period is less than the capacity of the compressor, the handle 150 may be forced upward and by the insertion of a suitable pin through the holes 151 and 159 the compressor's maximum output may be reduced to three-quarters of its potential output, or by inserting the pin in other pairs of mating holes, other still smaller maximum capacities may be obtained.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a pumping unit, in combination, a compound pump having double acting high and low pressure cylinders each provided with suitable inlet and discharge valves, means for closing off communication between the inlet valves at one end of both the high and low pressure cylinders and their respective supply spaces, means for closing the intake to the other end of said low pressure cylinder, pump discharge pressure controlled means controlling said first and second mentioned means, and relief valve means for venting said high pressure cylinder.

2. In a pumping system, a pair of compound pumps each having double acting high and low pressure cylinders which are provided with suitable inlet and discharge valves, means for unloading said pumps comprising intake closure means for one end of both the high and the low pressure cylinders of one of said pumps, intake closure means for the other end of the low pressure cylinder of said pump, similar unloading means for the second pump, pump discharge pressure controlled means for controlling serially

said several unloading means, and automatic relief means for the high pressure cylinders of said pumps.

3. In a compressor, in combination, an inlet valve, a valve seat therefor, and intake closure means including a valve coaxially arranged with respect thereto and movable rectilinearly axially thereof, and a valve seat cooperating with said second valve, said seat 10 being disposed parallel to said first seat.

4. In a compressor, in combination, coaxially disposed inlet and discharge valves, and intake closure means coaxially arranged with respect thereto.

15 5. In a compressor, in combination, an inlet valve, a valve disposed coaxially therewith adapted to control flow of fluid to said inlet valve, and a cylinder and piston coaxially arranged with respect to said valves for 20 operating said intake closure valve.

6. In combination with coaxially arranged inlet and discharge valve mechanism for a high pressure cylinder having a head, of intake closure means coaxially arranged with 25 respect to said inlet valve disposed in said head.

7. In a compressor, in combination, an inlet valve, a cage therefor, and a cover for controlling flow of fluid through said cage, 30 and actuating means through which said control is effected including a cylinder and piston coaxially arranged with respect to said inlet valve.

8. In combination with a compressor inlet and exhaust valve mechanism, of intake closure means coaxially arranged with respect thereto, and actuating means therefor, said closure means constituting an element of said actuating means.

40 9. In a compressor system including a plurality of pumping units cooperating in delivering air to a common discharge line, unloading means for each unit, and common control means for controlling the latter operative to cause successive unloading of 45 said units and including means for manually shutting down certain of said units.

10. In a compressor system including a plurality of pumping units cooperating in 50 delivering air to a common discharge line, unloading means for each unit, and common control means for controlling the latter operative to cause successive unloading of said units and including means for manually 55 shutting down certain of said units, while leaving the remaining units under the automatic control of said controlling means.

11. In a pumping mechanism, a plurality 60 of pumping units, common controlling means therefor adapted to control said units serially automatically, and manually operable means adjustable to remove certain of said units from automatic control while leaving the remainder subject thereto.

65 12. In a pumping mechanism, a plurality

of pumping units, common controlling means therefor adapted to control said units serially automatically, and manually operable means adjustable to remove certain of said units from automatic control while 70 leaving the remainder subject thereto and under identical controlling conditions.

13. In a pumping mechanism, a plurality of pumping units, common controlling means therefor adapted to interrupt the 75 pumping operation of said units at different predetermined pressures, and manually operable means adjustable to remove certain of said units from automatic control while leaving the remainder subject thereto.

14. In a pumping mechanism, a plurality of pumping units, common controlling means therefor adapted to interrupt the pumping operation of said units at different predetermined pressures, and manually 85 operable means adjustable to remove certain of said units from automatic control while leaving the remainder subject thereto at the same pressure conditions as when all are automatically controlled.

90 15. In a pumping mechanism, a plurality of pumping units, common controlling means therefor adapted to control said units serially automatically, and manually operable means adapted to act upon the automatic means and adjustable to remove certain of said units from automatic control 95 while leaving the remainder subject thereto.

16. In a pumping mechanism, a plurality of pumping units, common controlling 100 means therefor adapted to control said units serially automatically, and manually operable means adapted to act upon the automatic means and adjustable to remove certain of said units from automatic control 105 while leaving the remainder subject thereto and under identical controlling conditions.

17. In a pumping mechanism, a plurality of pumping units, common controlling 110 means therefor adapted to interrupt the pumping operation of said units at different predetermined pressures, and manually operable means adapted to act upon the automatic means and adjustable to remove certain of said units from automatic control 115 while leaving the remainder subject thereto.

18. In a pumping mechanism, a plurality of pumping units, common controlling means therefor adapted to interrupt the pumping operation of said units at different 120 predetermined pressures, and manually operable means adapted to act upon the automatic means and adjustable to remove certain of said units from automatic control 125 while leaving the remainder subject thereto at the same pressure conditions as when all are automatically controlled.

In testimony whereof I affix my signature.

ALEXANDER D. FERGUSON.
